UNITED STATES PATENT OFFICE.

ALEXANDER DELANEY, OF RICHMOND, VIRGINIA.

SPARK-ARRESTER FOR STEAM-BOILERS.

SPECIFICATION forming part of Letters Patent No. 224,001, dated February 3, 1880.

Application filed December 24, 1879.

To all whom it may concern:

Be it known that I, ALEXANDER DELANEY, of the city of Richmond, in the county of Henrico and State of Virginia, have invented new and useful Improvements in Spark-Arresters for Steam-Boilers, of which the following is a specification.

My invention relates to that class of spark-arresters more particularly designed for use on steam-boilers employed for agricultural purposes, or steam-engines employed in driving machinery for working up inflammable materials, to avoid fire being communicated to said materials by sparks escaping from the smoke-stack.

The invention is an improvement on that for which I have obtained Letters Patent of the United States dated November 5, 1878, and No. 209,668; and it consists, first, in providing the smoke-box of a steam-boiler with a smoke-pipe connected at the upper end with the smoke-stack and having its lower end to project below the boiler-flues, and in making said pipe adjustable vertically, whereby any number or all the flues may be uncovered, and the draft thereby regulated.

The invention further consists in the combination, with said adjustable smoke-pipe, of a diaphragm or deflector arranged below said pipe within the smoke-box in such manner as to deflect and conduct the products of combustion downwardly toward the bottom of the smoke-box before they reach the adjustable smoke-pipe.

The invention further consists in the combination, with the adjustable smoke-pipe and the deflector-diaphragm, of a water-reservoir and a series of deflecting-plates, forming ascending and descending flues or passages for the products of combustion before they reach the adjustable smoke-pipe, and whereby all cinders and sparks are arrested and thrown down into the water and extinguished.

The invention further consists in the combination, with the water-reservoir and the feed-pump, of a feed-pipe, whereby a jet of water is forced into said reservoir at each stroke of the feed-pump; and, lastly, the invention consists

in the combination, with the water-reservoir, of an adjustable waste or exhaust cock, whereby the level of the water in said reservoir may be adjusted, and thereby the draft regulated, while the surplus water is automatically drawn off.

Having thus described the general nature of my invention, I will now describe the same in detail, referring to the accompanying drawings, in which—

Figure 1 is a longitudinal vertical section, and Fig. 2 a section on line xx of Fig. 1, of a steam-engine embodying my invention; and Figs. 3 and 4 are like views, showing a slight modification in the construction and arrangement of certain parts.

Like letters of reference are employed to indicate like parts in the above figures of drawings wherever such occur.

A represents the boiler, or so much of the boiler as is necessary to illustrate my invention. B is the smoke-box, and C the smoke-stack. The latter is hinged to or removably connected with a base-pipe, D, by means of a hinge joint or joints, d .

The pipe D is of greater diameter than the prolongation C' of the smoke-stack, and forms an annular space, b , around said prolongation, for a purpose hereinafter described. The base-pipe D is contracted at its upper end, d' , to which the prolongation C' is rigidly connected, and above said contracted portion the base-pipe is provided with a seat or flange, d'' , and the hinge-knuckles or pin-bearings d^2 . The stack C, at its lower end, is also provided with a flange, c , or seat, and hinge-knuckle c' , and in this manner the stack C is removably connected with or hinged to the base-pipe D.

The prolongation C' of the stack projects downward to a point on a level with the arch of the smoke-box, as shown in Figs. 3 and 4, though I prefer to make it project slightly below the arch into the smoke-box, to afford a better bearing for the adjustable prolongation C' of the stack C, as shown by Figs. 1 and 2. This prolongation C' is fitted loosely upon prolongation C', and when in its normal position

rests upon a diaphragm, E, arranged transversely of the smoke-box B at a point below the boiler-flues *a* in such manner as to form the passage or flue *a'*, and, by the depending sides *e* of the diaphragm, the diving-flues F F 5 on opposite sides of the smoke-box.

Diaphragm E may be made flat, as shown in Figs. 3 and 4, or preferably of segmental shape, as shown in Figs. 1 and 2. It is provided in either construction with a central aperture, *e'*, surrounded by a flange or collar, *e''*, which serves as bearing for the adjustable prolongation C² of stack C. By means of this segmental shape of the diaphragm E, I obtain 15 pockets *e³*, within which a large proportion of the heavier particles of the products of combustion are precipitated and retained.

The arc described by the segment of the plate E is an arc of the circumference of the boiler, or practically so, and forms practically 20 a prolongation of the lower boiler-plates, provided with the passage *a'* for the products of combustion.

The prolongation C² of the smoke-stack C 25 may be adjusted upon the prolongation C' in any desired position by various mechanical devices, to any particular use of which I do not wish to limit myself, as such devices may be varied considerably and are of the province 30 of the skilled mechanic. For example, in Figs. 3 and 4, I have shown a system of toggle-levers, G, rigidly mounted upon a shaft, G', which has its bearings in the sides of the smoke-box. The arms *g* of said levers are pivoted to pins or trunnions *c²*, formed upon or 35 attached to the lower end of the vertically-adjustable prolongation C², as shown. One end of the shaft G' projects some distance outside of the smoke-box, and carries a ratchet, *g'*, 40 with which engages a pawl, *g²*, pivoted upon the smoke-box.

By means of the hand-lever *g³* upon the outer end of shaft G' the latter is rotated, and through the toggle-levers G the prolongation 45 C² is raised to any desired point, sliding upon prolongation C' into the recess *b*, formed by said prolongation and the base-pipe D. The pawl *g²*, engaging with the ratchet *g'*, serves to hold the pipe in any desired position.

50 In Figs. 1 and 2 I have shown an arrangement of rack and pinion by means of which the same result may be obtained. A toothed rack, H, attached to prolongation C², is made to rise and fall with said prolongation by 55 means of the pinion *h*, located within a housing or box attached to or formed upon the lower end of the base-pipe D. The shaft of said pinion projects through the housing *d³* and carries a hand-lever, *g³*, and said shaft and pinion, and 60 with them the prolongation C², may be locked into any desired position by means of a ratchet and pawl, as above described, or by means of a pin, *h'*, passing through the base-pipe D and made to engage the teeth of the rack-bar H, as 65 shown. A similar result may also be obtained by a system of chains and pulleys, as will be readily

understood. I have found that some such provision is necessary in order to enable me to establish a direct draft when starting the fires, because when the pipe C² is seated upon the 70 plate E and the products of combustion are made to follow the devous route hereinafter described the draft is not sufficient to start the fires quickly and generate steam.

As the fire gains in intensity and steam is 75 generated the prolongation C² is gradually lowered to force the products of combustion to assume a downward course, thereby gradually diminishing the draft until sufficient steam has been made, when the prolongation C² is 80 lowered onto its seat upon diaphragm E, the prolongation C² thus virtually serving as a damper.

I is a water-reservoir attached to the lower end of or formed by the lower end of the smoke-box B. It is of like diameter, but longer, and forming an open mouth, *i*, in front of the smoke-box, as shown, in order to afford easy access thereto for the purpose of removing the heavier products of combustion precipitated therein. 85 To avoid a counter-draft through this open mouth *i*, the front wall of the smoke-box B is prolonged sufficiently so that its lower edge will at all times be immersed in the water of the reservoir, as shown at *b'*.

The reservoir I is divided longitudinally into five compartments by means of diaphragms K K' K', either perforated at their base or so attached to the reservoir as to leave a passage, *i'*, below each diaphragm for the free circulation of the water throughout the compartments. These diaphragms are of varying heights, the former, K, being slightly higher than the latter, K'.

The diaphragm E carries on its under side 105 two zigzag diaphragms, *e³*, projecting downward into the compartments formed by the diaphragms K K', as do the depending sides *e* of the diaphragm E, which project into the compartments formed by diaphragms K and 110 the side walls of the smoke-box. In this manner a continuous zigzag passage is formed, through which the products of combustion are made to pass before they reach the stack, 115 when prolongation C² is seated upon diaphragm E.

The lower edges of the depending sides *e* of diaphragm E and of the zigzag diaphragms *e³*, as well as the upper edges of diaphragms K K', are bent outwardly, forming deflecting 120 edges, against which the products of combustion impinge, and by means of which the heavier particles—such as cinders, ashes, &c.—are arrested and precipitated into the water below.

The reservoir I is automatically fed by means of a pipe, L, connected with the feed-pump M, in such manner that at each stroke of the pump a small jet of water is forced into the reservoir, the flow of which may, if desired, be regulated 130 by a stop-cock, *l*.

In view of economizing fuel by regulating

the draft independently of the adjusting of prolongation C^2 , and in conjunction with the diaphragm E, by means of the water in reservoir I, and in order to automatically draw off the surplus water, I use an adjustable waste cock or bib, N, of any usual or desired construction. The one shown in the drawings consists of a pipe, n, bent at its inner end, and rotated by means of a handle, n', within its stuffing-box. It is obvious that when the bent portion of the waste-cock is elevated the level of the water within the reservoir is correspondingly elevated, and the passage for the products of combustion between said water-level and the under side of diaphragm E correspondingly contracted, and vice versa, while any excess of water is automatically drawn off, no matter what position the waste-cock may be in. By these means I effect a considerable saving in fuel.

Having described my invention, what I claim is—

1. In a steam-boiler, the hinged or removable smoke-stack C, in combination with the smoke-box, the base-pipe D, and the pipe-section C', the latter being arranged to form a continuation of said smoke-stack and an annular chamber or recess within said base-pipe, substantially as and for the purpose specified.

2. In a steam-boiler, the hinged or removable smoke-stack C, in combination with the smoke-box, the base-pipe D, the pipe-section C', and the pipe-section C², arranged to project within the smoke-box to a point below the boiler-flues, and to form with section C' a continuation of said smoke-stack C, substantially as and for the purpose specified.

3. In a steam-boiler, the combination, with the smoke-stack and smoke-box, of a vertically-adjustable pipe-section arranged to form a prolongation of said smoke-stack within the smoke-box, for the purpose of imparting a downward course to the products of combustion and for regulating the draft, as set forth.

4. In a steam-boiler, the combination, with the smoke-box having a base-pipe, D, the smoke-stack having a prolongation, C', arranged within said base-pipe to form an annular chamber, b, of the vertically-adjustable pipe-section C², adapted to slide upon said section C' and be withdrawn from the smoke-box into the recess or chamber b, substantially as described, for the purpose specified.

5. In a steam-boiler, the combination, with the smoke-box and smoke-stack, the latter projecting into the former to a point below the boiler-flues, of a diaphragm, E, arranged to form the diving-flues F, for the purpose of conducting the products of combustion below said diaphragm previous to their reaching the smoke-stack, substantially as and for the purpose specified.

6. In a steam-boiler, the combination, with the smoke-box, the base-pipe D, stack C, prolongation C', and the diaphragm E, of the vertically-adjustable prolongation C² of said

stack, whereby the products of combustion may be conducted below said diaphragm to the stack, or directly to the latter, and the draft regulated, substantially as described, for the purpose specified.

7. In a steam-boiler, the combination, with the smoke-box and the smoke-stack having an adjustable prolongation, C², arranged as described, of a segmental diaphragm, E, arranged to form the pockets e³ and the diving-flues F, substantially as and for the purpose specified.

8. The combination, in a steam-boiler, of the smoke-box B, the smoke-stack C C' C², and the diaphragm E, of a water-reservoir, I, all arranged in relation to each other substantially as and for the purpose specified.

9. In a steam-boiler, the smoke-box provided with a diaphragm below the level of the boiler-flues and a water-reservoir located below said diaphragm, in combination with means, substantially as described, for regulating the draft by varying the level of the water within the reservoir to enlarge or contract the space between said water-level and the diaphragm, substantially as described, for the purpose specified.

10. In a steam-boiler, the combination, with the smoke-box B, smoke-stack C C' C², and the diaphragm E, of the reservoir I and its diaphragms K K' K', all arranged and operating substantially as and for the purpose specified.

11. In a steam-boiler, the combination, with the smoke-box B, smoke-stack C C' C², the diaphragm E, arranged to form the diving-flues F and the smoke-passage a', and the diaphragms e⁴, of the reservoir I and its diaphragms K K' K', all arranged and operating substantially as and for the purpose specified.

12. In a steam-boiler, the combination, with the smoke-box and the prolongation C² of the smoke-stack, the diaphragm E, having depending sides e, the lower edges of which are bent outwardly, and the zigzag depending diaphragms e⁴, having their lower edges similarly bent, of the reservoir I and the diaphragms K K' K', of varying height, and having their upper edges bent outwardly, all arranged and operating substantially as and for the purpose specified.

13. In a steam-boiler and spark-arrester, the combination of the smoke-box B, the smoke-stack C C' C², projecting within the smoke-box to a point below the boiler-flues, and the diaphragm E, located below said smoke-stack, with the water-reservoir I in the bottom of the smoke-box, and an adjustable waste cock or bib for the purpose of regulating the draft by varying the level of the water in said reservoir, substantially as described.

14. The combination, with the smoke-box B, having its front wall prolonged, as described, of the water-reservoir I, projecting in

front of said smoke-box and being open at top, substantially as described, for the purposes specified.

15. In a steam-boiler and spark-arrester provided with a water-reservoir located at the bottom of the smoke-box, the combination of devices, substantially as described, for automatically supplying said reservoir with water and automatically exhausting the excess or surplus water when brought to the desired level,

arranged to operate in relation to each other in the manner and for the purpose specified.

In witness that I claim the foregoing I have hereunto set my hand this 16th day of April, 1879.

ALEXR. DELANEY.
